UNITED STATES PATENT OFFICE.

ROY W. SCHWEIKER, OF LANSDALE, PENNSYLVANIA.

LIGHTING FIXTURE.

Application filed May 3, 1925. Serial No. 27,531.

This invention relates to lighting fixtures and, more particularly, to means for fastening electric sockets to side-wall fixtures.

Despite the fact that electric lamp sockets are supposed to be adequately insulated and that porcelain fixtures, such as side-wall fixtures, to which they may be attached, may be of porcelain which is an insulating material itself, nevertheless the authorities in 10 many localities will not approve a fixture of this character if the lamp socket is attached to the fixture by an exposed metal fastening. The objection arises because of the danger of electric shock to a person who 15 may have one hand on the fixture and another hand on a lavatory faucet, as fixtures of this character are very generally used in bath rooms and lavatories.

To overcome the foregoing defect and to 20 obviate the necessity of providing unsatisfactory insulating fastenings in fixtures of this character, as well as to meet the requirements laid down by the authorities without having to provide a special construction of 25 socket, I have devised an improved fastener for securing the socket to the fixture, whether the socket be seated in the fixture, or, supported by a bracket as is commonly done in electric fixtures of the "candle" type.

30 My improved fastener or connection is, in its broadest aspect, an attaching means which is countersunk in the porcelain fixture in such fashion that there is no projecting metallic part which may be touched 35 by the fingers of any one taking hold of the fixture or turning the lamp on or off. In its secondary aspect, my invention embodies a screw adapter, plug, or bushing, which is of a size enabling it to be screwed into the 40 nipple on the bottom of the lamp socket or on the bracket which supports the lamp socket in those well known constructions which are ordinarily intended for connection to a tubular arm or fixture, combined 45 with a screw which passes through a hole in the porcelain fixture and is countersunk so that no part of the connecting screw is exposed. Preferably, a gasket of fiber or of rubber is used in connection with the socket 50 or with the bracket which supports the socket, to afford a more or less flexible seat so that the lamp socket will be firmly secured and yet will not tilt when the screw is tightened. Porcelain fixtures sometimes 55 have irregularities at the point where the socket or the bracket is intended to rest and,

indeed, there sometimes exists a concavity at this point. By using the gasket, a secure connection is attained.

No claim is made to the socket or its supporting bracket or to the nipple for the socket or bracket as these are well known constructions, it being the purpose of the invention to utilize well known constructions in that respect.

60 The design of the porcelain bracket is not claimed herein as both designs disclosed in the drawings are set forth in design applications copending herewith.

65 Certain embodiments of the present invention are hereinafter described and claimed and are disclosed in the accompanying drawings in which:

70 Figure 1 is a front elevation, the porcelain fixture and the gasket being in section;

75 Figure 2 is a side elevation, partly in section;

Figure 3 is a detail bottom view of the bracket and bushing;

Figure 4 is a detail perspective of the 80 lower part of the bracket;

Figure 5 is a similar view of the bushing; and

85 Figures 6 and 7 are views corresponding, respectively, to Figs. 1 and 2, showing the invention applied to a socket which rests directly on the fixture.

A side wall porcelain fixture such as may be used in a bath room or lavatory, is shown in Figs. 1 and 2 at 1. An ordinary electric 90 lamp socket 2 is supported by a two-part adjustable bracket 3 of well known construction. The bracket 3 is provided with an internally screw-threaded nipple 4 which, as shown, is adapted to screw onto the end of 95 a tubular wall fixture, according to present practice. Instead of modifying the bracket section 3' which has the nipple 4, I provide means whereby this well known commercial construction may be used without modification, in carrying out my invention.

100 With that end in view, I provide an externally screw-threaded adapter or bushing 5 which screws into the nipple 4 and is provided with a slot 6 across its bottom for the 105 convenient application of a screw-driver so that it may be screwed into the nipple 4. The bushing 5 is provided with an internal screw-threaded hole 7.

110 The fixture 1 has an opening 8 extending vertically through its lower part and communicating at its upper end with the con-

cavity 9 in the fixture. In the lower part of the fixture 1 is a concavity or countersink 10 with which the opening 8 communicates. A screw 11 which passes through the opening 8, has its upper part engaged with the screw-threaded hole 7 of the bushing or adapter 5. The head of the screw lies in the countersink 10 so that it is completely protected and cannot be touched by the fingers of anyone touching the fixture 1 or turning the electric lamp on or off.

A gasket 12 may be provided as a seat for the lower end of the section 3' of the lamp bracket but it is not necessary to use this gasket in the form of the invention shown in Figs. 1 and 2, although it is preferable to do so as the gasket provides for suitable seating of the bracket and enables the screw 11 to be drawn up tightly to effect such seating without likelihood of the bracket and socket assuming an inclined position or of getting loose.

The invention is shown in Figs. 1 and 2 in connection with a fixture and lamp socket particularly intended for use in connection with an artificial "candle" 13.

In Figs. 6 and 7 my invention is shown in connection with a porcelain side wall fixture where the socket 2 is intended to be contained within the concavity 9 so that the lamp or electric bulb will appear just above the cup 14. This form of lamp socket is usually provided with an internally screw-threaded nipple 15 projecting downwardly from its base. As previously described, I provide a bushing or adapter 5 such as shown in Fig. 5 and a screw (although a shorter one) 11 which enters the hole 7 in the bushing and passes through a hole 8 in the bottom of the cup 14. There is a concavity or countersink 10 to guard the head of the screw, as previously described. As shown by dotted lines at 13 in Fig. 6, a short "candle" could be used in connection with the embodiment of Figs. 6 and 7 but this is not usually the practice.

What I claim is:

1. In a side wall lighting fixture, the combination with the fixture proper having a base adapted to lie flatwise against the side wall and provided with a bracket extending laterally therefrom, said bracket being provided with a concavity, of a lamp socket having an attaching device located within said concavity, and fastening means for said attaching device, said fastening

means being independent of the aforesaid bracket and extending through the said bracket into the concavity and operable from the exterior of said bracket and countersunk on the exterior thereof.

2. In a side wall lighting fixture, the combination with the fixture proper having a base adapted to lie flatwise against the side wall and provided with a bracket extending laterally therefrom, said bracket being provided with a concavity, of a lamp socket having an attaching device located within said concavity, and an adjustable screw for said attaching device, said adjustable screw being independent of the aforesaid bracket and extending through the said bracket into the concavity and operable from the exterior of said bracket, the bracket having a countersink which houses the head of the screw.

3. In a side wall lighting fixture, the combination with the fixture proper having a base adapted to lie flatwise against the side wall and provided with a bracket extending laterally therefrom, said bracket being provided with a concavity, of a lamp socket having an attaching device located within said concavity, a gasket interposed between the attaching device and bottom of the concavity, and adjustable fastening means for said attaching device, said fastening means being independent of the aforesaid bracket and extending through said bracket into the concavity and operable from the exterior of the bracket, said fastening means serving to draw the attaching device against the gasket, whereby the gasket anchors or seats the attaching device in the concavity.

4. In a side wall lighting fixture, the combination with the fixture proper having a base for attachment to the side wall and an outstanding bracket which is provided with a concavity, of a lamp socket having an attaching device provided with an internally screw threaded nipple located in said concavity, an externally screw threaded bushing or adapter engaged with the internal screw threads of said nipple, and a fastening screw engaged with the interior of said bushing and connecting the bushing to the bracket, said fastening screw extending through said bracket and operable from the exterior thereof, the bracket being provided with a counter-sink which houses the head of the screw.

In testimony whereof I affix my signature.

ROY W. SCHWEIKER.
